Specification for Design.

Patented Nov. 5, 1912.

Application filed August 14, 1912. Serial No. 715,121. Term of patent 14 years.

To all whom it may concern:

Be it known that I, JOHN E. MARSDEN, a citizen of the United States, resident in the city of Philadelphia, State of Pennsylvania, have invented a new, original, and ornamental Design for a Vehicle-Vase.

My new, original, and ornamental design for a vehicle vase is illustrated in the accompanying drawing, in which:

Figure 1 is a front elevational view of the same. Fig. 2 is a side elevational view of the same. Fig. 3 is a top plan view of the same.

I claim:

The ornamental design for a vehicle vase as shown.

In testimony whereof I have hereunto affixed my signature in the presence of the two subscribing witnesses.

JOHN E. MARSDEN.

Witnesses:

ELEANOR T. McCALL,
BEATRICE WHITNEY.
